SPRINKLER HEAD ASSEMBLY

Arthur C. Rowley, Drexel Hill, Pa., assignor to
Globe Automatic Sprinkler Company, Philadelphia, Pa., a corporation of Pennsylvania

Application November 18, 1949, Serial No. 128,073

5 Claims. (Cl. 169—38)

1

This invention relates to improvements in automatic sprinkler installations and a principal object of the invention is to provide a mounting for existing sprinkler heads which will tend to render the heads less obtrusive.

More specifically stated, a primary object of the invention is to provide simple and effective means in the form of a novel adaptor fitting for in-setting the sprinkler heads in the ceiling so that they will project below the latter to the minimum extent consistent with their function.

The invention will be more readily understood by reference to the attached drawings, wherein;

Figs. 1 and 2, are respectively, top and bottom perspective views of a sprinkler head assembly made in accordance with the invention;

Fig. 3 is a side elevational and partial sectional view of a sprinkler head installed in accordance with the principle of the invention;

Fig. 4 is a view in perspective of one of the elements of the assembly;

Fig. 5 is a view in perspective of another of the elements of the assembly with a portion thereof broken away;

Figs. 6 and 7 are inverted perspective views of another of the elements of the assembly showing the upper and undersides of the element respectively, and;

Fig. 8 is a fragmentary view in perspective of the upper end of the sprinkler frame.

Fig. 9 is an enlarged fragmentary sectional view showing in greater detail a portion of the structure of Fig. 3.

With reference to the drawings, the assembly forming the subject of the present invention comprises a sprinkler frame 1 of conventional type, this frame comprising an upper hollow body member 2 (see Fig. 8) having a through passage 3 and the usual threaded extension 4 by means of which the frame is mounted in the sprinkler pipe system. Attached to and extending from the body member 2 are two arms 5 and 6 which meet at their lower ends, as shown in Fig. 3, to form a solid juncture 7 having a threaded aperture for reception of the upper threaded end 8 of a spreader 9 of conventional form. At its underside, the body member 2 has a nozzle extension 11 for the bore 3, and the lower end of the nozzle is normally sealed by a closure disc 12 which seats on the lower end of the nozzle as shown in Figs. 2 and 3 and which is normally held to its seat by means of a linkage assembly 13 including a heat responsive release element 14. The necessary tension required to hold the closure disc 12 in place against

2

the pressure within the pipe system is effected by means of the screw 8, between the upper end of which and the disc 12, the linkage assembly 13 is confined. Insofar as described, the sprinkler head is conventional.

In the present instance, a discharge pipe of the sprinkler system is indicated by the reference numeral 15. To this pipe is threaded a reducing fitting 16, and into the lower end of this fitting is threaded the stem 4 of the sprinkler frame as shown in Fig. 3. A ceiling structure 17 conceals the pipe 15 and is provided with an opening 18 through which the sprinkler head projects downwardly into the room space below the ceiling.

15 In accordance with the present invention, an adaptor fitting 21 is provided at the upper end of the sprinkler head, said fitting being supported on the sprinkler frame. The fitting is in the form, in the present instance, of a disc having a socket 22 shaped to receive and to neatly embrace the upper end of the sprinkler frame. To this end, the socket 22 is generally rectangular in form for reception of the rectangular body portion 2 of the frame, and at opposite sides of the rectangular socket the side walls are recessed, as indicated at 23, for reception of the upper ends or shoulder portions of the depending arms 5 and 6. Thus the upper end of the sprinkler frame fits neatly within and effectively closes the socket opening 22 and at the same time forms a stable seat for the fitting 21 upon which the fitting is supported in fixed position, it being noted that the form of the socket and of the mating upper portion of the sprinkler frame precludes relative rotational movements of these parts about the axis of the bore 3. As shown in Figs. 1, 2, 6 and 7, the fitting 21 has an upper radial flange 24 in which are provided recesses 25 for engagement with a suitable wrench, and the cylindrical lower portion 26 of the member may be externally threaded as indicated at 27.

45 In assembly, as previously set forth, the sprinkler head is threaded into the fitting 16 and is thereby secured in the sprinkler system. Attachment of the head to the fitting 16 may be effected from below the ceiling 17 by means of a suitable wrench engaged with the notches 25 of the flange 24 of the member 21. In order to facilitate this operation, the member 21 is anchored to the frame of the sprinkler head by a spring retainer 28, best shown in Fig. 4, this member being engaged below the lowermost thread of the stem 4 of the frame and behind an annular shoulder on the member 21 as indicated at 29 in Fig. 3, the outer peripheral portion of the

retainer seating resiliently in an annular recess 31 in the upper surface of the said member. As shown in Fig. 4, the retainer 28 is open at one side, as indicated at 32, so that this element may be slipped laterally into the operative position described above.

With the sprinkler head thus installed in the pipe system and projecting downwardly through the opening 18 to a minimum extent consistent with the proper distribution of the water by the spreader 9, the member 21 will lie approximately at the level of the ceiling 17, as illustrated in Fig. 3. It will be apparent that the dished form of the underface 33 of the member 21 aids in minimizing the extent to which the sprinkler head extends below the ceiling level and also affords a desirable ornamental appearance.

In order to close the space between the sides of the member 21 and the wall of the ceiling opening 18 and to afford a desirably finished appearance, an annular plate 34, as best shown in Fig. 5, is provided, this member having a flange 35 which closely embraces the depending cylindrical portion 26 of the member 21 and which has small pressed in bosses 36 adapted to resiliently interlock with the threads 27, as shown in Fig. 9, to hold the plate 34 in the position in which it is shown in Fig. 3. This holding means is such, however, as to render the plate 34 readily displaceable by any substantial pressure from above, which precludes possibility of the weight of the ceiling structure 17 being imposed upon the sprinkler head and, through the head, upon the pipe system.

I claim:

1. In a sprinkler head assembly, a frame comprising a hollow body member forming a discharge nozzle, means at one end of said nozzle for connecting the frame in a sprinkler system, a closure for the other end of said nozzle, and thermally responsive retaining means for said closure including a support structure extending from the body member outwardly beyond the end of the nozzle, and a fitting formed with a recessed socket shaped to conform with and to receive the intermediate portion of the body member between the ends of the nozzle, said fitting being detachably supported on and embracing the body member and extending transversely from the latter to form a shield for said connecting means.

2. In a sprinkler head assembly, a frame comprising a hollow body member forming a discharge nozzle, said member being threaded at one end to afford a means for connecting the frame in a sprinkler system, a closure for the other end of said nozzle, and thermally responsive retaining means for said closure including a support structure extending from the body member outwardly beyond the end of the nozzle, a fitting detachably supported on and embracing the body member and extending transversely from the latter to form a shield for said connecting means, said fitting being formed with a socket shaped to conform with and to receive an intermediate

portion of said body member between the ends of the nozzle, and a resilient element detachably inserted between the inner end of said thread and the confronting face of the fitting to releasably anchor the fitting to the frame.

3. In a sprinkler head assembly, a frame comprising a hollow body member forming a discharge nozzle, means at one end of said nozzle for connecting the frame in a sprinkler system, a closure for the other end of said nozzle, and thermally responsive retaining means for said closure including a support structure extending from the body member outwardly beyond the end of the nozzle, a fitting detachably supported on and embracing the body member and extending transversely from the latter to form a shield for said connecting means, said fitting being formed with a socket shaped to conform with and to receive an intermediate portion of said body member between the ends of the nozzle, and the said intermediate portion of the body member being shaped to preclude relative rotation of the fitting and frame about the axis of the nozzle, and said fitting being formed for engagement by a wrench for threading the frame in the said system.

4. In a sprinkler head assembly, a frame comprising a hollow body member forming a discharge nozzle, means at one end of said nozzle for connecting the frame in a sprinkler system, a closure for the other end of said nozzle, and thermally responsive retaining means for said closure including a support structure extending from the body member outwardly beyond the end of the nozzle, and a fitting detachably supported on and embracing the body member and extending transversely from the latter to form a shield for said connecting means, the face of the fitting which confronts the closure end of the nozzle being concave.

5. In a sprinkler head assembly, a frame comprising a hollow body member forming a discharge nozzle, means at one end of said nozzle for connecting the frame in a sprinkler system, a closure for the other end of said nozzle, a thermally responsive retaining means for said closure including a support structure extending from the body member outwardly beyond the end of the nozzle, a fitting detachably supported on and embracing body member and extending transversely from the latter to form a shield for the connecting means, and an annular plate element detachably supported on and extending outwardly from the periphery of said fitting, said element being adjustable on the fitting axially of the nozzle.
